Inventor

F. F. Bradley

UNITED STATES PATENT OFFICE.

FRANKLIN F. BRADLEY, OF CHICAGO, ILLINOIS.

METHOD OF PACKAGING AND MEANS FOR MAKING MIXED PAINTS.

1,360,085.

Specification of Letters Patent. Patented Nov. 23, 1920.

Application filed June 26, 1920. Serial No. 392,063.

To all whom it may concern:

Be it known that I, FRANKLIN F. BRADLEY, a citizen of the United States, and a resident of the city of Chicago, county of Cook, and State of Illinois, have invented new and useful Improvements in Methods of Packaging and Means for Making Mixed Paints, of which the following is a specification.

10 My invention relates to the method of packaging and means for making or compounding mixed paints, and resides in so packaging mixed paints that they may be merchandizable by dealers without modification, in the original packages containing the same, the paints, however, being contained in these packages in such accurately proportioned and related quantities, so distributed in filled and partially filled cans, 15 that the dealers may produce various colors and shades and packaged quantities of paint, by discharging cans of paint into larger cans partially filled with base paint forming the necessary complement in quantity 20 and kind, each larger can being sufficiently empty to receive all of the paint from a smaller can to insure accuracy in the proportioning of the paint ingredients finally contained in the larger can in which the new 25 paint is completely formed and disposed of to the consumer.

In practising my invention I procure in segregated lots equal portions of a basic mixed paint, such portions being multiples 30 of a unit of quantity. I also procure in said units of quantity, base modifying mixed paints in a series of shades or colors or both so arranged that each of the series, when mixed with a segregated lot of said basic 35 paint, will produce a product uniform with a predetermined one of the other paints of the additive series.

In the drawings:

Figure 1 shows in conventional diagram 40 a series of large containers, each containing a predetermined quantity of base paint.

Fig. 2 shows a series of smaller containers containing additive paint in different shades, and

Fig. 3 is the same for paint of another color.

In the drawing, 1 represents a container filled three-fourths full of white paint base while 2 represents a receptacle having yellow base and 3 represents one of the same containers made full by adding to the paint

in one of the containers 1, the paint from the receptacle 5 which is filled with (in this case pink) coloring paint. The contents of this can when added to the contents of can 1 produces a composite result of the shades indicated and this shade in turn is the same as the shade 5^a. If the contents of 5^a be added to 1 the result would have the shade and color of 5^b and this in turn would produce 5^c. I have shown five shades.

In Fig. 3 I show a series of green shades 6, 6^a, 6^b, 6^c, 6^d, arranged likewise to cooperate with the white.

It is possible also to use additional base 70 as 2, shown here as yellow, thus building up other series of colors or shades which, however, are not matched to the paints of that additive series.

In a specific embodiment of my invention 75 I produce a base for intermixture with prepared mixed paints of different shades of the same color or of different colors and partially fill portable cans with substantially equal portions of this base. I also 80 produce a plurality of mixed paints so predetermined in shade and color as to match the mixed paints finally to be produced and when sub-divided into substantially equal quantities are receivable in partially filled cans of base paint and will each produce, with the base in a base can, a final mixed 85 paint of a shade different from that of the employed initially mixed paint. Substantially equal sub-divided quantities of these 90 initially produced mixed paints are stored in packages which may themselves be sold by the dealers, or the contents of which may be transferred to the partially filled base cans to produce mixed paints of other 95 shades, as stated. These additive mixed paints are so graduated in shade or color or both as to match the last one of the completed line of mixed paints. In accordance 100 with this plan, the initially produced mixed paints are preferably so graduated in shade or color or both that each, when added to the base in a base receptacle will produce a final mixed paint of the shade or color of the initially mixed paint next to that of the employed mixed paint. In accordance 105 with this preferred embodiment of my invention, a store keeper may carry a complete line of initially produced graduated mixed paints. These initially produced 110 paints may be supplied to the consumer in their own cans, or the contents of these

cans may be introduced into base cans with the definite assurance that paints of like shades and color to those carried in stock (except the last) will be produced, but in 5 larger packaged quantities. In practice it would be customary to supply quart portions of the initially produced mixed paints in quart cans and three quart portions of the base in gallon cans into one of which 10 a quart of initially produced mixed paint may be supplied from a can thereof that is next the gallon of mixed paint to be produced by this mixture, this gallon of mixed paint being, by means of my process, of the shade of a quart can of initially produced mixed paint. The dealer is thus enabled to 15 mix and supply a gallon of mixed paint of the desired shade and color in a single gallon can.

20 A dealer may carry one base paint in gallon cans three-quarters full and say eight series of base modifying paints with five shades or colors in each series in quart quantities. As an example, the base paint might 25 be white and the eight series of base modifying paints might consist of blue, green, gray, yellow, tan, brown, pink or red and stone color, each in five different depths of shade. With such a stock the dealer could furnish 30 his customer with any one of forty shades or colors in quart cans and any one of forty shades or colors in gallon cans. Thirty-two of the forty shades or colors in quarts would be identical with those of the gallons. Eight 35 of the shades or colors in quarts would be deeper in shade than the deepest of the gallons and eight of the shades or colors in gallons would be lighter in shade than the lightest of the quarts. This is as it should 40 be because the trimming shades or colors of a building are sold most largely in the smaller size and the darkest shades or colors are used for trimming purposes. The lighter shades or colors are used most 45 largely for painting the body of a building and are more especially required in the large size packages.

If instead of carrying only one base paint the dealer carries in gallon cans three-quarters full another base of some color such as 50 yellow which could well be the same as the darkest of his series of shades of yellow in the base modifying paints, and if he mixed with packages of this yellow base, quarts of 55 the forty colors or shades of base modifying paints he would have doubled or produced eighty shades or colors in gallon cans.

In the practice of my invention it is desirable if not necessary that my base mixed 60 paint and my series of additive mixed paints be prepared of materials, both pigments and vehicles, which will behave well chemically and physically with each other. The colors and oils must be mixed and ground from 65 such materials that the resultant product

will be unaffected by any untoward precipitate or change of color.

The base paints and the additive base modifying paints are complete and useful mixed paints in themselves, and have 70 strengths, colors, viscosities and freedom from chemical or physical properties that might cause any harmful results from their admixture; they are capable of uniting to form complete and useful mixed paints of 75 their predetermined color and shade.

It will be noted that my invention is dependent primarily upon successfully matching colors at the factory and takes away from the retailer and the consumer all elusive perplexities attendant upon this most difficult thing. It should be noted that the quart cans, to use the illustration above, are 80 each filled with exactly one quart of paint, not merely with a quart of oil to which 85 some weight and bulk of pigment is added. The quart of paint thus had, must, when added to three quarts of base, make four quarts of paint having exactly the shade and color of the next can of the series. Since 90 any given quart of the mixed gallon carries only one-fourth the tinting reaction of the original quart used, the next quart (below) must have only one-fourth that of the original quart. How to get this is by no means 95 an easy problem, as the color producing agents must be so proportioned to the oil that they together make just one quart. It is not necessary to declare here how this is done, since all the varying and shifting factors, the age and character of the oil, the brightness and depth of the pigment's color, its purity, and other factors as well, must be reckoned with and the final determinant is in many cases a subjective one.

100 Among the advantages of my invention are those of gain to the retailer and purchaser in ease of operation, the sufficiency of small stocks, low investment on the part of the dealers with widened field of selection for their customers and means for 105 freshly mixing paint not long before final sale. The average age of a can of paint in the hands of a dealer employing my process is but a fraction of that hitherto obtaining 110 in ready prepared paints. This is true because the dealer needs to buy but a little paint at a time, his reorders and turnover of stock being frequent and his stock thus kept 115 fresh and therefore better.

120 The series of additive paints must have, relative to the base, tinting strengths expressed by the symbols a , $\frac{a}{4}$, $\frac{a}{16}$, etc., where a stands for the tinting strength where used 125 first in the series.

Having thus described my invention I claim as new and desire to secure by Letters Patent the following:

130 i. In combination a number of gallon

cans each holding three quarts of paint of the same uniform color and, a number of quart cans each full of paint of the same color but shaded in series one can to each shade, the shades being so arranged in the series that when the paint of one of the quart series is mixed with the paint of a gallon can, four quarts of a paint having the shade of the next of the series is produced, whereby there will be in all five quarts of one shade.

2. Means for producing mixed paints including a base parceled in gallon cans, three quarts per can; and, parceled in quart quantities for admission to the gallon cans, a plurality of additive mixed paints constituting a series graduated in shades from that of the aforesaid base and having, with reference to its relative tinting strengths indicated by a , $\frac{a}{4}$, $\frac{a}{16}$, $\frac{a}{64}$, etc.

3. Means for producing mixed paints, said means including a base of uniform character parceled into uniform multiples of a

unit quantity and, parceled into said unit quantities, a plurality of additive mixed paints constituting a series graduated from that of the aforesaid base and having, with reference to it, relative coloring values so arranged that each when added to a parceled quantity of the base, will produce a product uniform with one of the other paints of the series.

4. That method of packaging mixed paints which consists in packaging in uniform quantities which are multiples of a unit quantity, a basic mixed paint, and packaging in units of said unit quantity, base modifying mixed paints in a series so arranged that each when mixed with a package of the basic paint, will produce in a multiple of the unit quantity, a mixed paint exactly matching another mixed paint of the series, at a predetermined distance in the series from the first added paint.

In testimony whereof I have hereunto set my hand.

FRANKLIN F. BRADLEY.
